UNITED STATES PATENT OFFICE.

BERARDINO GIZZI, OF TURTLE CREEK, PENNSYLVANIA.

BRACKET FOR SUPPORTING WINDOW SHADES AND CURTAINS.

Application filed August 15, 1923. Serial No. 657,503.

To all whom it may concern:

Be it known that I, BERARDINO GIZZI, a citizen of the United States, residing at Turtle Creek, in the county of Allegheny and State of Pennsylvania, have invented a new and useful Improvement in Brackets for Supporting Window Shades and Curtains, of which improvement the following is a specification.

10 My invention relates to improvements in supports for window shades and curtains; the object of my invention is the production of a device of this kind that can be manufactured very cheaply and is efficient in 15 operation. I accomplish this object by means of device hereinafter more specifically described, reference being had to the accompanying drawings forming a part hereof, in which

20 Fig. 1 is a front elevation, the curtain and its supporting bracket being omitted.

Fig. 2 is a side elevation of the same, with curtain and bracket shown.

25 Fig. 3 is a plan view of the spool and curtain bracket.

Referring to said drawings, 1 is the window frame to the sides of which at the top are secured the brackets 2, 3, formed of a continuous piece of heavy wire in which are 30 formed depressions 4, 5 which respectively constitute bearings for the roller 6 to which the shade 7 is attached, and of the roller 8 to which the curtain 9 is attached. The said brackets are formed of heavy wire having

35 at one end a screw threaded portion or shank for fastening the brackets to the window frame, and the bracket 2 and 3 comprises a portion *a* which is bent at right angle to the main portion across the face of the spool or bobbin 10, forming a guard 40 to limit the outward movement of the cord 11 and serving to produce great rigidity in the brackets. The lower side or bottom of the shade has secured thereto a bar 12 of some considerable weight to enable the shade 45 to be lowered by gravity. The lower end of said cord 11 is provided with a plate 13 having upwardly projecting serrations adapted to engage upon pins secured in the plate 14 attached to the frame of the window for the purpose of holding the shade 50 at any desired elevation as shown in Fig. 2.

Having described my invention what I claim and desire to secure by Letters Patent is:

55 A bracket for supporting window shades and curtains, comprising a continuous piece of heavy wire, having a threaded shank, and a plurality of depression forming bearings for respectively a shade roller and a curtain, and having a portion between said bearings extending laterally at right angles to the main portion of the bracket for increasing the rigidity of the bracket and forming a guide for the operating cord.

60 In testimony whereof, I have hereunto signed my name.

BERARDINO GIZZI.
